UNITED STATES PATENT OFFICE.

JOHN EPPLER, OF PHILADELPHIA, PENNSYLVANIA.

MACHINE FOR MAKING PAPER CONES.

Application filed August 4, 1921. Serial No. 489,669.

To all whom it may concern:

Be it known that I, JOHN EPPLER, a citizen of the United States, residing at Philadelphia, county of Philadelphia, and State of Pennsylvania, have invented a new and useful Improvement in Machines for Making Paper Cones, of which the following is a full, clear, and exact description, reference being had to the accompanying drawings, which form a part of this specification.

My invention relates to paper cones for use as spools for holding yarn in textile mills. The object of my invention is to make said cones, in a continuous process, from a roll of paper. The invention comprises a machine adapted to effect such object. In the embodiment of my invention herein disclosed, such machine includes means for feeding paper from a roll; means for applying gum to a portion of the paper, leaving ungummed the part that forms the inner surface of the cone; means for trimming one edge of the paper, removing the flimsy beveled edge and giving it a contour which will readily enter the slot in the conical mandrel used in making the cones; means for cutting the blank to form a cone and entering it into the mandrel; means for winding the blank about the mandrel, means while applying pressure thereto to insure adhesion of the gummed surface; means to trim the ends of the cone, finishing it to specified length; and means for discharging the finished cone.

Anyone skilled in the art will fully understand and appreciate the novel features and advantages of my invention from the following description of my machine, in connection with the accompanying drawings, in which:

Fig. 1 is a plan view with parts broken away or omitted for the sake of clearness.

Fig. 2 shows the shape of the blank for forming a cone.

Fig. 3 is a sectional elevation of the machine taken on the line 3—3 of Fig. 1.

Fig. 4 is an elevation of the left side of the machine as shown in Fig. 1 with parts omitted.

Fig. 5 is a sectional elevation taken on line 6—6 of Fig. 1.

Fig. 6 is an enlarged view showing the mandrel with the paper blank in position for engagement therewith.

Fig. 7 is a section at 7—7 Fig. 1.

Fig. 8 is a section showing a plan of the circular cutting and turning table.

Fig. 9 is a detail sectional view showing the blank holding mechanism.

Fig. 10 is a section at 10—10, Fig. 1.

The roll of paper *a* is mounted in brackets below the machine table *b*, as shown in Figure 3, and carries a pulley at one end provided with a spring tension cord *c* for imparting resistance to unwinding. The paper is led upward from the roll and over a rod *d* at just about the table level. Thence it passes between the large rollers *e* and *f*, around roll *f* against which it is held by a spring-pressed roller *g*, up and around a roller *h*, supported on brackets at a height above the table, and down again and under a roller *i*, which delivers the paper at the working level of the cutting knives. The elevated position of roller *h* is adjustable and is for the purpose of allowing sufficient time for the gum to set on the paper.

Rollers *e* and *f* are intermittently driven as will be hereinafter described. The lower one, roller *e*, is the gumming roll and dips into a bath *l* in the table carrying liquid gum for the purpose. It is not desired to gum the entire surface of the paper, however, as that would make the finished hollow cone have a gummed inner surface. To avoid this, roller *e* has a cut-away portion *e'*, shown clearly in Fig. 1, which does not contact with the paper and is made of such shape as to have a triangular portion of the surface, represented by the angle *e''* on the blank shown in Figure 2, uncoated with gum.

The paper passes from roll *i*, over a cutting plate *j* and between the feed rolls *k* and *k'*, which are intermittently driven with rolls *e* and *f*. While the rolls are stationary and the paper lies on the cutting plate *j*, the irregular cutting blade *l* is brought down, cutting the edge of the paper as shown at *l'*, Figures 1 and 2. This cutter, as shown in Figures 3 and 7, is mounted on posts *m* on table *b*, and is normally held up by spring *n*. Post *o*, connected with the cutter, is linked to one arm of a lever *p*, pivoted to a fixed support. The other end of lever *p* carries a roll which is acted upon by a cam *q* on shaft *r*, which will be described with the driving mechanism.

After the irregular edge l' has been cut, the paper is fed forward and deposited on the turn table t beneath the semi-circular cutter s . A pivoted holding frame u is then swung down to clamp the blank upon the turn table. The cutter s is then caused to descend and cuts the blank as shown in Figure 2.

Turn table t is then caused to turn throughout an arc of about 90° , from the position shown in Figure 1 to that shown in Fig. 8. As it gets to this position, a horizontal finger v on the holding frame overrides a pin on the lower end of a rod w , Figure 9. When the turn table has finished its motion, and the irregular cut edge l' of the paper blank held thereon is entered into slot x in the conical mandrel y , this rod w is caused to rise, lifting the holding frame u and releasing the blank.

As will be seen in Fig. 6, the slot in the conical mandrel is a mere slit x for about half its length, narrow enough to firmly hold the edge of the paper. The remainder of the slot, at the small end of the cone, is flared wide for the reception of the paper. When the paper is first presented to it, the mandrel is in a retracted position and the projecting portion of the paper freely enters horizontally into the flared portion of the slot. The mandrel is then moved lengthwise by its cam 40 to the relative position shown in Fig. 6, which causes the projecting edge of the paper to slide into the narrow portion x of the slot where it binds sufficiently to hold for wrapping about the mandrel. At the same time the turn table is given a slight backward turn partly withdrawing the edge of the paper so that it will extend less deeply into the mandrel, leaving just enough lap to hold the paper for wrapping as desired, and avoiding the objectionable triangular shaped lap commonly formed by machines now in use.

At this time the holding frame is lifted as previously described, releasing the blank, and the mandrel is given a rotary motion, wrapping the paper blank about it to form the desired cone. As before stated, the portion of the blank forming the first wrap about the mandrel is free of gum, but the succeeding two or more wraps are gummed on the top or inner surface and adhere to the first wrap and to each other to form a solid cone of several thicknesses of paper. A wiper 12 is provided for pressing the wraps together on the mandrel as they are being formed. Wiper 12 extends parallel to the conical surface as shown in Figure 5, and is carried on the end of a lever 13, the other end of which, as seen in Figure 10, is spring-held against a cam 14 on shaft r' . Cam 14 allows the spring to press wiper 12 against the cone while the latter is making ten or a dozen revolutions so that the paper

cone is not merely given the number of turns required to form it, but while spinning around is acted upon by the wiper, to give a smooth and finished outer surface.

During these extra rotations the paper cone is cut to length at both ends by cutter wheels 15, mounted to rotate freely on a frame 16 vertically slidable in a standard 17 on table b . To this end a lever 18 is pivoted to said standard, one end of said lever carrying an adjusting screw 19 which contacts with the top of frame 16, and the other end of said lever being actuated by a cam 20 on shaft r' . Cutters 15 are normally spring-held up out of action, and at the right moment cam 20 raises its end of lever 18 which causes frame 16 carrying the cutters to descend into the conical surface of the mandrel, one near its point, trimming off the tip of the paper cone, and the other near the large end, acting similarly.

There are circles of fibre inserted flush with the surface of the cone, as indicated at 21, 21, Figure 6, where the cutters act, in order to furnish a backing which will not dull the steel cutters. The turning of the mandrel and paper cone causes the cutters to revolve as soon as they make contact and the result is a clear finished cut at both ends of the paper cone, which is now finished.

The mandrel then ceases turning, the cutters are raised and the wiper lowered out of action, when the mandrel is withdrawn longitudinally through its slide 32 and cone discharge band 23. This band slides in the cylindrical portion of the spindle and is supported by rods 24 slidable in the casing of slide 22. Just at the time the mandrel starts to withdraw, one of these rods is given a forward kick by a lever 25 acted on by a cam 26 on shaft r' as shown in Figure 1. This kick gives band 23 a preliminary forward motion against the large end of the cone, causing it to loosen from the mandrel. In the following withdrawal of the mandrel the finished paper cone falls through an opening in table b into a chute or receptacle not shown.

All the operations of the machine are driven from a shaft 30, which may receive its motion from a counter shaft or reducing gearing, as most convenient, and may carry a hand wheel for turning it over if desired.

Shaft 30 operates shaft r' by bevels 31 and at its opposite end shaft r' operates through bevels 32 to turn shaft r , so that the three shafts operate continuously when the machine is running.

Shaft 30 carries a cam 33 for operating turn table t . Cam 33 acts upon a roller on an arm 34 pivoted to a standard on table b . Arm 34 extends below the table and is connected beneath by a link with a rack 35 slidable horizontally in brackets depending from the table. Meshing with rack 35

is a pinion 36 carried by the turning post of turn table *t*. A spring 37 holds arm 34 against cam 33, and on the low part of the cam, as shown in Figure 5, the turn table 5 is held in its normal position for receiving the end of the paper strip. When the high part of cam 33 acts on arm 34, rack 35 is drawn over, which turns pinion 36 and the turn table is turned to deliver the cut blank 10 to the mandrel.

For operating the mandrel longitudinally, shaft 30 carries a cam 40, which acts on an arm 41 pivoted to the frame of the machine below table *b* and extending up there- 15 through. The upper end of arm 41 is linked to an arm 42 depending from a standard on table *b*. Arm 42 is likewise connected by a link 43 with a sliding rod 44 mounted in brackets to move parallel with the table. A 20 block on rod 44 turnably carries the end of spindle 45 carrying mandrel *y*. Thus cam 40 acts through arms 41 and 42 to slide rod 44 and with it the mandrel, at the proper moment for discharging a paper cone.

25 The mandrel is intermittently rotated from a gear 46 on shaft *r'* provided with a toothed portion and a blank portion. Through reducing gears 47 this intermittent gear acts upon a pinion 48 splined upon 30 spindle 45 of the mandrel. The arrangement is such that the spindle 45 may be moved longitudinally through pinion 48 to project the mandrel to receive the edge of the blank, whereupon the toothed portion 35 of gear 46 acts upon gearing 47 to turn pinion 48 thereby rapidly revolving the spindle and mandrel.

As before stated, when the paper blank is fed to the mandrel, holding frame *u* is 40 raised from the surface of the turn table by rod *w* lifting up finger *v*. There is a latch 50 on the under side of the turn table for holding the frame in open position when it has been thus raised, a spring 51 connecting the latch and the frame acting to 45 both raise the latch and draw the frame down. While the paper blank is being wound onto the mandrel, the turn table is returned to its initial position, the holding frame being held open by the latch. In this 50 initial position of the turn table, the end of the latch underrides one end of a lever 52 pivoted to a fixed support, the other end of lever 52 resting on the low part of a cam 55 53 on shaft *r'*. At the proper time, when the paper has been fed onto the turn table and the feeding mechanism is at rest, cam 53 acts to turn lever 52 to open latch 50 and spring 51, together with its own weight, 60 brings frame *u* down to clamp the paper on the turn table preparatory to the semi-circular cutting action.

Continuously revolving shaft *r* carries the cam *q* for operating the irregular edge cutter *l*. Shaft *r* also carries a facial gear 55

provided with teeth for only a portion of its periphery, to intermittently drive the gumming and feed rolls. At the time desired to feed the paper, the tooth portion of gear 55 acts upon a pinion attached to a gear 56 to 70 rotate this gear. Gear 56 meshes with a gear 57 on the shaft of roller *f*, and gear 57 is in turn in mesh with a gear 58 connected with the gumming roll *e*. Thus at the proper time these rolls draw the paper 75 from the paper roll *a*.

A sprocket wheel 60 on the shaft of roll *f* is connected by a chain with a sprocket 61 on the shaft of feed roller *k*. Feed rollers *k* and *k'* are connected at their opposite ends 80 by equal gears 62 so that they are both rotated positively to feed the paper at the same time rollers *e* and *f* act, and the sprocket wheels are of such size as to insure equal feeding at both sets of rolls. 85

Semi-circular cutter *s* is carried on vertical posts 63 slidable in a fixed supporting frame 64 arranged above the turn table *t*, and is normally held in upper position by springs 65. The cutter is lowered to perform its cutting operation in the following manner.

A horizontal shaft 66 is supported in bearings 67 in the upper part of frame 64. Discs 68 on this shaft have camways 69 in 95 their opposing faces, wherein travel rollers 70 mounted on guiding yokes 71 carried by posts 72 mounted on cutter *s*. Thus the turning of shaft 66 lowers and raises yokes 71 and with them the semi-circular cutter *s*. 100

A hand wheel 73 may be provided on shaft 66 for turning the mechanism over, but it is normally driven by a gear 74 connected by a train of gearing 75 with a gear 76 on shaft *r*. Therefore, shaft 66 is continuously turning and the movement of cutter *s* is determined by the shape given cam slots 69. 105

There is a cam 77 on shaft 66, which operates on one end of a centrally pivoted lever 78, the other end of which actuates vertical rod *w*, against its spring. When lever 78 is on the high part of cam 77, the pin on the lower end of rod *w* underrides finger *v* of the holding plate *u*, as previously described, and shown in Figure 9. 110

Having now fully described my invention, what I claim and desire to protect by Letters Patent is:

1. In a machine for making paper cones, a conically-shaped mandrel provided with a longitudinal slot relatively narrow toward the wide end of the mandrel and substantially wider toward its narrow end, the wider portion affording a ready means of entering the blank and the narrow portion enabling the mandrel to grip a narrow inserted edge of the blank preparatory to wrapping. 120

2. In a machine for making paper cones, the combination with a conically-shaped mandrel having a longitudinal slot, means 130

to cut and shape the blank, means to insert an edge of the blank into that portion of the slot toward the narrow end of the mandrel, and means to impart to the mandrel a longitudinal movement relatively to the blank, thereby causing said edge of the blank to enter the portion of the slot toward the wide end of the mandrel.

3. In a machine for making paper cones, 10 the combination with a conically-shaped mandrel having a longitudinal slot, relatively narrow toward the wide end of the mandrel and relatively wide toward its narrow end, means to cut and shape the blank, 15 means to insert an edge of the blank into the wide portion of the slot, and means to impart to the mandrel a longitudinal movement relatively to the blank, thereby causing said edge of the blank to enter the narrow portion of the slot.

4. In a machine for making paper cones, the combination with a conically-shaped mandrel having a longitudinal slot, means to insert 25 an edge of the blank into that portion of the slot toward the narrow end of the mandrel, means to impart to the mandrel a longitudinal movement relatively to the blank, thereby causing said edge of the blank to enter the portion of the slot toward the wide end of the mandrel, means operating 30 after the blank is inserted in the mandrel to retract the blank relatively to the axis of the mandrel, and means to rotate the mandrel.

5. In a machine for making paper cones, the combination with a conical-shaped mandrel having a longitudinal slot, means to cut 40 from a strip of material a substantially semi-circular blank having an edge one part of which is inclined relative to the other, means to transfer the blank from the point at which it was cut to a point where it is wound on the mandrel, means to shift the mandrel axially to cause the above mentioned edge of the blank to enter the slot therein, and means to rotate the mandrel to wind the blank thereon while in its shifted position.

6. In a machine for making paper cones, the combination with a conically-shaped mandrel having a longitudinal slot, means to cut and shape the blank to afford an edge one part of which is inclined relatively to the other, means to insert said inclined edge of the blank into the part of the slot nearer the narrow end of the mandrel, and means to move the mandrel longitudinally relatively to the blank, thereby causing said inclined edge to engage the part of the slot nearer the wider end of the mandrel.

7. In a machine for making paper cones, the combination with a conically-shaped mandrel having a longitudinal slot, means to cut and shape the blank to afford an edge

one part of which is inclined relatively to the other, means to insert said inclined edge of the blank into the part of the slot nearer the narrow end of the mandrel, means to move the mandrel longitudinally relatively to the blank, thereby causing said inclined edge to engage the part of the slot nearer the wider end of the mandrel, and means to retract the blank relatively to the axis of the mandrel, thereby leaving, preparatory to 75 wrapping, a relatively narrow strip of approximately uniform width within the body of the mandrel.

8. In a machine for making paper cones, the combination of a mandrel having a longitudinally extending slot, blank-actuating mechanism movable first toward, and subsequently away from, the axis of the mandrel, and means to move the mandrel longitudinally between said blank-actuating movements; said three movements operating respectively to enter the blank in the slot, position it longitudinally therein and govern the width of the edge of the blank within the slot of the mandrel preparatory to rotation; and means to rotate the mandrel.

9. In a machine for making paper cones, the combination of blank-feeding mechanism, a turn table to which the blank is fed, means to cut the blank into approximately semi-circular form and to cut and shape the diametric edge of the blank, a rotatable slotted mandrel, means to turn the turn table and thereby project a cut and shaped edge of the blank into the slot of the mandrel, and means to rotate the mandrel.

10. In a machine for making paper cones, the combination of a turn table, a rotatable mandrel, feeding mechanism adapted to convey a blank to the turn table, a holder adapted to hold the blank on the turn table, a cutter adapted to cut the blank on the turn table preparatory to winding, and means to turn the turn table and thereby project it into operative relation with the mandrel.

11. In a machine for making paper cones, the combination with a conical-shaped mandrel having a longitudinal slot, means to cut from a strip of material a substantially semi-circular blank having an edge one part of which is inclined relative to the other, means to transfer the blank from the point at which it was cut to a point where it is wound on the mandrel, means to shift the mandrel axially to cause the above mentioned edge of the blank to enter the slot therein, means to rotate the mandrel to wind the blank thereon while in its shifted position, rotary cutters, and means for shifting the cutters into trimming relation to the mandrel while the mandrel is still in its winding position to trim the ends of the formed cone.

12. In a machine for making paper cones,

- the combination of blank cutting and shaping means, a conically-shaped mandrel, means to deliver the shaped blank to the mandrel and engage it therewith, means to 5 rotate the mandrel and thereby wind the blank into a conical form, a pair of cutters in operative relation with the mandrel and adapted to trim off the ends of the blank while the same is positioned on the mandrel, 10 and rings of material different from that of which the mandrel is composed applied to the mandrel and flush with the outer surface thereof and alining with said cutters.
13. In a machine for making paper cones, 15 means for feeding a continuous strip of paper through the machine, means to apply adhesive material to portions of one side of the strip, cone forming mechanism, blank cutting mechanism, and means for delivering the blank from the cutting mechanism to the cone forming mechanism, said cutting mechanism being positioned with relation to the adhesive applying means to so cut the blank from the strip that the interior and 20 exterior of the finished cone will be free of adhesive material.
14. In a machine for making paper cones, 25 means for feeding a continuous strip of paper through the machine, means to apply adhesive material to portions of one side of the strip, cone forming mechanism, blank cutting mechanism, an oscillating table for delivering the blank from the cutting mechanism to the cone forming mechanism, and a 30 clamp for holding the cut blank on the turn table during its transfer.
15. In a machine for making paper cones, 35 the combination of means for gumming a portion of one side of a strip of paper, leaving certain portions ungummed, cutting mechanism to form blanks from the gummed strip, means for trimming off the flimsy edge of the blank, a slitted conical mandrel, means for entering the trimmed edge into 40 the slitted mandrel, means to rotate the 45 mandrel, a wiper adapted to press on the blank as it is wound on the mandrel, and means for cutting off both ends of the wound and pressed blank on the mandrel.
16. In a machine for making hollow cones 45 of a given length from a strip of paper, the combination of a gumming roll with a portion of its surface cut away, means for trimming the edge of the paper strip, means for cutting out a blank, a conical mandrel having a longitudinal slit toward its base and a communicating relatively wide opening toward its point, means for entering the trimmed edge of the paper blank into said slit, means to turn the mandrel, a wiper 60 adapted to press the wrappings of the cone closely together, cutters operating against the mandrel near both ends whereby the cone is cut to a certain length, and means for withdrawing the mandrel to discharge 65 the finished cone.
17. In a machine for making hollow cones 70 from a strip of paper, the combination of means for feeding the paper strip intermittently, means operative while the paper is stationary for trimming an edge and cutting out a blank therefrom, a slitted mandrel, a turn table adapted to receive said blank, means for holding the blank on the turn table, means for turning the turn table whereby 75 the trimmed edge of the blank enters the slitted mandrel, means for releasing the holding means on the turn table, means for rotating the mandrel to wrap the blank into a cone, spaced revoluble cutters, means to 80 bring said cutters into contact with the mandrel while the latter is rotating, and means to discharge the finished cone.
- In testimony of which invention, I have hereunto set my hand, at Philadelphia, Pa., 85 on this 3rd day of August, 1921.

JOHN EPPLER.
